CONDIMENT SHELF

Louis F. Kolarik, 606 Ardmore Ave., Erie, Pa.

Filed Jan. 26, 1962, Ser. No. 68,530

Term of patent 14 years

(Cl. D44—29)

FIG. 1 is an isometric view of a condiment shelf embodying my new design;

FIG. 2 is an enlarged scale side elevational view thereof;

FIG. 3 is a cross-sectional view of one of the shelf units shown in FIG. 2;

FIG. 4 is a top plan view of one of the shelf units, a portion being broken away for convenience of illustration;

FIG. 5 is an isometric view of the base unit;

FIG. 6 is an enlarged scale isometric view of a spacer unit; and

FIG. 7 is an enlarged scale side elevational view of the cap unit.

This application is a continuation-in-part of my earlier filed application Serial No. D. 52,843 of October 1, 1958, now abandoned.

I claim:

The ornamental design for a condiment shelf, as shown and described.
